Primary Examiner — Susan Moon Lee(74) *Attorney, Agent, or Firm* — Womble Carlyle Sandridge & Rice, LLP**CLAIM**

The ornamental design for a hummingbird feeder, as shown and described.

DESCRIPTION

FIG. 1 is a perspective view of a hummingbird feeder in accordance with the present invention, wherein a perspective view from the opposite side is substantially a mirror image of FIG. 1;

FIG. 2 is a front elevation view of the hummingbird feeder of FIG. 1;

FIG. 3 is a rear elevation view of the hummingbird feeder of FIG. 1;

FIG. 4 is a left elevation view of the hummingbird feeder of FIG. 1;

FIG. 5 is a right elevation view of the hummingbird feeder of FIG. 1;

FIG. 6 is a top plan view of the hummingbird feeder of FIG. 1; and,

FIG. 7 is a bottom plan view of the hummingbird feeder of FIG. 1.
